UNITED STATES PATENT OFFICE.

PHILLIPP SCHOLTES, OF MOUNT OLIVER, PENNSYLVANIA.

HAMMER.

SPECIFICATION forming part of Letters Patent No. 759,556, dated May 10, 1904.

Application filed September 9, 1903. Serial No. 172,517. (No model.)

To all whom it may concern:

Be it known that I, PHILLIPP SCHOLTES, a citizen of the United States, residing at Mount Oliver, in the county of Allegheny and State 5 of Pennsylvania, have invented new and useful Improvements in Hammers, of which the following is a specification.

My invention pertains to hammers of the nail-placing type; and it consists in the peculiar and advantageous construction herein-after described, and particularly pointed out in the claims appended.

In the accompanying drawings, Figure 1 is a view, partly in section and partly in elevation, of a hammer-head constructed in accordance with my invention, the sectional portion being taken on the line *xx* of Fig. 2. Fig. 2 is a section taken on the line *yy* of Fig. 1, and Fig. 3 is a transverse section taken in the 20 plane indicated by the line *zz* of Fig. 1.

Similar letters designate corresponding parts in all of the several views of the drawings, referring to which—

A is the handle, and B the head, of the hammer constituting the preferred embodiment of my invention. The head is shown as having a poll *a*, an eye *b*, and a hatchet-blade *c*; but I desire it understood that the blade may be omitted or claws used in lieu of the same, 30 also that the head may be formed integral with the handle or connected thereto in any approved manner without involving a departure from the scope of my invention.

C is a longitudinally-disposed wall formed integral with the poll *a* of the head at the inner side of said poll and having a transverse notch *d* in its edge; D, a longitudinal integral wall arranged parallel to the wall C and having a recess *e* in its inner side, Fig. 2; E, 40 a recess formed in the inner side of the poll at the inner ends of the walls C D; F, a kerf formed in the inner side of the poll *a* in alignment with the recess *e* of wall D and gradually increased in depth toward its forward 45 end, as best shown in Fig. 1, and G a spring, preferably of brass, arranged in the recess *e* of wall D and pivotally connected, adjacent to one end, to said wall D through the medium of a rivet *F*, as shown, or other suitable means.

50 When it is desired in practice to use the

hammer in the ordinary manner—*i. e.*, to drive nails placed with the hand—the spring G is pushed, through the medium of a nail or other device, down into the kerf F, where it will remain, because of the tendency of its 55 free end to spring laterally. With the spring in such position there is no liability of it being injured in the event of the user missing a nail which he is driving.

When the hammer is to be used to place nails 60 precedent to driving the same home, a nail or other pointed instrument is placed in the notch *d* of wall C and in engagement with an aperture *g* in the spring and is used to move the spring out of the kerf F and into the position 65 shown in Figs. 1 and 2.

With the spring G in the last-mentioned position it will be observed that when a nail is placed with its head in the recess E and its shank between the free portion of the spring 70 and the wall C said nail will be securely held and may be readily placed by a light blow, also that after the nail is placed the hammer may be readily lifted out of engagement with the nail and used to drive the same home. 75

The rear end of the spring G is beveled, as shown in Fig. 1, in order to permit of the spring being placed in the kerf F and yet prevent it from moving downwardly beyond the position shown in Fig. 1. 80

It will be readily appreciated from the foregoing that my improvements add but very little to the cost of a hammer and do not render the same cumbersome or unsightly in appearance.

I have entered into a detailed description of 85 the construction and relative arrangement of the parts embraced in the present and preferred embodiment of my invention in order to impart a full, clear, and exact understanding of the same. I do not desire, however, to 90 be understood as confining myself to such specific construction and arrangement of parts, as such changes or modifications may be made in practice as fairly fall within the scope of my invention as claimed. 95

Having described my invention, what I claim, and desire to secure by Letters Patent, is—

1. In a hammer-head, the combination with a poll having longitudinal walls, at one side, 100

adapted to receive a nail between them, and also having a longitudinal kerf in alinement with the space between the walls; of a spring arranged longitudinally between said walls, 5 and pivotally connected adjacent to one end to one of the walls; said spring being adapted when not in use, to be placed in the kerf in the poll.

2. In a hammer-head, the combination with 10 a poll having a longitudinal wall, at one side, provided with a notch *d*, a longitudinal wall, arranged parallel to that first mentioned, and having a recess *e* in its inner side, a recess *E*

arranged in rear of the walls, and a kerf *F* in alinement with the recess *e*; of a spring pivotally connected adjacent to one end to one wall and arranged in the recess *e* thereof, and having an aperture adjacent to its free end. 15

In testimony whereof I have hereunto set my hand in presence of two subscribing witnesses. 20

PHILLIPP SCHOLTES.
